(57) **CLAIM**

The ornamental design for a bell-type pipe hanger, as shown and described.

DESCRIPTION

FIG. 1 is a perspective view showing a first embodiment of my new design for a pipe hanger;

FIG. 2 is a front view thereof;

FIG. 3 is a top view thereof;

FIG. 4 is a right side view thereof;

FIG. 5 is a bottom view thereof;

FIG. 6 is a rear view thereof; and,

FIG. 7 is a perspective view showing a second embodiment of my new design for a pipe hanger.

The material shown in dotted line is included for illustration and environmental purposes only and is not intended to form a part of the illustrated design.
